UNITED STATES PATENT OFFICE

172,898

SPINDLE FOR A YARN WARPING FRAME

Elphege Nadeau, Blackstone, Mass.

Application February 12, 1954, Serial No. 28,991

Term of patent 3½ years

(Cl. D92—15)

To all whom it may concern:

Be it known that I, Elphege Nadeau, a citizen of the United States, residing at Blackstone, in the county of Worcester and the State of Massachusetts, have invented a new, original, and ornamental Design for a Spindle for a Yarn Warping Frame, of which the following is a specification, reference being had to the accompanying drawing, forming part thereof.

Fig. 1 is a front elevation of a spindle for a yarn warping frame embodying my new design.

Fig. 2 is a side elevation thereof.

Fig. 3 is a top plan view thereof.

Fig. 4 is a bottom plan view thereof.

I claim:

The ornamental design for a spindle for a yarn warping frame, as shown.
